UNITED STATES PATENT OFFICE.

ADAM GABRIEL, OF CHICAGO, ILLINOIS, ASSIGNOR TO WILLIAM F. DOENGES, OF SAN ANTONIO, TEXAS.

LOCK FOR HANDLES OF SAFES OR VAULTS.

Application filed January 28, 1924. Serial No. 688,911.

To all whom it may concern:

Be it known that I, ADAM GABRIEL, a citizen of the United States, residing in the city of Chicago, county of Cook, State of Illinois, have invented a certain new and useful Improvement in Locks for Handles of Safes or Vaults, and declare the following to be a full, clear, and exact description of the same, such as will enable others skilled in the art to which it pertains to make and use the same, reference being had to the accompanying drawings, which form a part of this specification.

The present invention relates to that type of handle for actuating the shaft that throws the bolt mechanism on the doors of safes, or vaults, or for other purposes which, until the insertion of a key, is freely rotatable on the shaft and cannot actuate or turn the latter until the handle is locked or clutched to the same by the operation of the key; and has for its object to produce a construction which will offer a maximum resistance to tampering by mechanical means or by heat or both.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a central axial section taken through one of my improved devices in position on a door; Fig. 2 is a view similar to Fig. 1, some of the elements that are shown in Fig. 1 being shown in elevation; Fig. 3 is a section taken approximately on line 3—3 of Fig. 2; Fig. 4 is a section taken approximately on line 4—4 of Fig. 2; Fig. 5 is a section taken approximately on line 5—5 of Fig. 2; Fig. 6 is a longitudinal section through the sliding socket or clutch member, only a fragment of the latter, and also a fragment of the actuating cam being shown; and Fig. 7 is an elevation of the actuating cam and the cooperating part of the socket member or clutch.

Referring to the drawings. 1 represents a strong cup-shaped casing, preferably cylindrical in shape and having thick walls, within the closed end of the casing is a lock, preferably a key lock of the cylinder type, the cylinder being indicated at 3. For convenience of manufacture, this lock is preferably fitted into a thick ring 4 that is held in the casing by being forced into the same or otherwise. The closed end of the casing has an opening 5 for the insertion of a key, not shown, into the key hole 6 of the lock. While the casing may, of itself, serve as a knob or handle yet, in order to secure an increased leverage, the casing may be provided with a handle member. In the arrangement shown, there is a radially projecting handle 7 that is fixed at one end to the cylindrical wall of the casing and has a part 8 projecting inwardly into a socket formed in the lock adapter; thus serving to pin the adapter to the casing.

In the open end of the casing is detachably secured a closing element which may conveniently take the form of a disc 9 screwed into the casing and preferably provided with a central hub portion 10 projecting in opposite directions therefrom. Arranged between the member 9 and the lock adapter is a sleeve 11 of substantially the same diameter as the interior of the casing, the sleeve serving as a spacing device and also as an inner wall for the casing, whereby the casing becomes double-walled. The closing element may be locked in place by means of a lock nut 12 surrounding the outer portion of the hub and engaged with the screw threads in the casing. Headless setscrews 13, may be inserted in the lock nut and engage the closing element to prevent the lock nut from being accidentally turned. The parts are so proportioned that when they are assembled the outer end face of the hub 10 and the outer face of the lock nut are flush with the end of the casing so as to afford a large solid bearing face against a door 14, when in use.

The actuating shaft 15 for the bolt mechanism on the door extends through the thick-

ness of the door and through the hub 10 into the casing, the hub forming a long bearing for rotatably supporting the casing on the shaft. The shaft has thereon, beyond the inner end of the hub 10, an annular projecting flange 16, between which and the inner end of the hub is a suitable antifriction thrust bearing 17 which, in the arrangement shown, is a ball bearing. In applying the device to the door, the shaft is inserted through the latter from the front, bringing the end of the casing into engagement with the door. A suitable detachable holding device 18 which may also be a part of the bolt-actuating means is secured upon the shaft on the rear side of the door in such a way as to tend to draw the shaft through the door and thus bring the end of the casing into close contact with the outer face of the door and thus avoid the presence of a crack or crevice into which a wedging instrument could be inserted by the burglar or other person.

Normally, as heretofore stated, the casing is rotatable on the shaft. In order to clutch the casing to the shaft so as to compel the two to turn together, suitably, a simple clutching mechanism controlled by the lock 2, is arranged within the space in the casing enclosed by the sleeve 11. The immediate clutching means consists of a thick sleeve 20 having a sliding fit within the sleeve 11 and being shorter than the latter; the sleeve 20 being interlocked within the casing in such a manner that the two must rotate together. In the arrangement shown, there are fixed to the lock adapter a plurality of long dowel pins 21 arranged parallel with the axis of the shaft 15 and extending lengthwise through the wall of the sleeve 20. These dowel pins therefore serve both as interlocks and as guides for the sleeve. The sleeve 20 has an internal diameter preferably such that it will fit easily over the inner portion of the hub 10, and it is preferably of such length that when it is moved as far as it will go toward the right, as viewed in Fig. 1, it still slightly overlaps the hub. Consequently, even though the cylindrical wall of the casing and the sleeve 11 should be perforated, the sleeve 20 would still form a barrier to prevent access to the shaft. The sleeve 20 has at about the middle a partition 22 extending transversely of the same. This partition has at the center a noncircular opening 23 registering with a noncircular part 24 on the inner end of the shaft; the opening 23 and the part 24 of the shaft being shown as square. The extreme inner end of the shaft is preferably made round, as indicated at 25; the parts being so proportioned that when the sleeve 20 is in what may be termed its idle position, as shown in Figs. 1 and 2, the socket 23 is clear of the square portion of the shaft but still

surrounds the round portion 25. It will be seen that when the parts are in the positions shown in Figs. 1 and 2, the casing is free to rotate on the shaft and therefore it is impossible, through turning the casing or handle, to operate the shaft whereas, when the sleeve 20 is moved toward the left as far as it will go, it becomes a socket wrench interlocked with the shaft and, since it is also interlocked with the casing, the turning of the casing or handle will produce a corresponding turning movement of the shaft.

Movement of the wrench member 20 from its idle position toward its working position is effected in the arrangement shown by means of springs 26, arranged in sockets opening out through the inner or rear face of the lock adapter 4, these springs being constantly under pressure so that they always tend to move the wrench member into its working position and hold it there. The wrench member is moved into and positively locked in its idle position by suitable wedging or cam means actuated by the lock cylinder 3. The immediate cam or wedging means consists of an inwardly directed annular part 27 on the right hand end of the wrench member as viewed in Figs. 1 and 2. For convenience in manufacture, the part 27 is preferably made in the form of a lateral projection from a circular plate or disc 28 engaged with the end of the sleeve 20 and, in fact, forming the effective end of the sleeve; the part 27 fitting into the interior of the sleeve. There is also a rotatable cam or wedge device 29, arranged within the socket wrench made between the partition 22 and the part 27. Either or both of the elements 27 and 29 may have cam or wedging faces, each having a wedging face, in the arrangement shown, in order to make the pitch less than would be necessary if there were only one inclined face. There is a thrust bearing 30, conveniently a ball bearing, between the inner end face of the shaft 15 and the member 29. The member 29 is connected to the cylinder 3 of the lock by being loosely engaged upon a square end 31 of a fitting or cap 32 set upon and fastened to the projecting end of the lock cylinder by a pin 33 passing through the member 32 and the lock cylinder transversely of the axis of the latter. By leaving the cam or wedging member 29 loose on the fitting 32, a key by means of which the lock cylinder is turned, in operating the device is relieved from all stresses except those resulting from the rotation of the cam or wedging member, because said member can adjust itself slightly, as the necessity arises, to insure that it will at all times be properly seated against the thrust bearing 30.

I have shown a headed screw 34 at the inner end of the fitting 32, but the purpose

of this screw is simply to form a centering device for the ball retainer of the thrust bearing 30.

It will thus be seen that I have produced 5 a simple and novel handle device which may be locked to a shaft or spindle for turning the same or which may be left loose on the shaft or spindle to prevent the latter from being operated. It will also be seen that 10 access to the shaft is made so difficult that at least three separate cylindrical walls must be broken down before the end of the shaft outside of the door can be reached, and therefore my improved device is fully as 15 burglar-proof as the ordinary safe door itself.

While I have illustrated and described with particularity only a single preferred form of my invention, I do not desire to be 20 limited to the exact details thus illustrated and described; but intend to cover all forms and arrangements that come within the definitions of my invention constituting the appended claims.

25 I claim:

1. In combination, a casing, a shaft extending through a wall of the casing, said wall having an inwardly-directed hub surrounding said shaft, the shaft having at the 30 inner end beyond the hub a noncircular portion, a member housed in said casing and interlocked therewith so as to be held against rotation therein and be free to slide relatively thereto between a working and 35 an idle position in the direction of the length of said shaft, said member having an annular part that surrounds the said hub in all positions of said member and a part fitting upon said noncircular part of the 40 shaft only in the working position of said member, and key-controlled means for moving said member between its said positions.

2. In combination, a casing, a shaft extending into the casing, a member housed 45 in the casing and interlocked with the same so as to be held against rotation relatively to the casing and be free to move in the casing in the direction of the length of the shaft between a working position and an 50 idle position, said member and said shaft having parts adapted to couple them together when said member is in its working position and permit the casing and said member to turn on the shaft when said member 55 is in the idle position, spring means tending to move said member into its working position, and key-controlled mechanism for moving said member into and locking it in its idle position.

60 3. In combination, a cup-shaped casing, lock mechanism arranged in the closed end of the casing, said casing having a key opening in the vicinity of said mechanism, a closing element lying wholly within and 65 detachably secured in the open end of said

casing, a shaft extending through and rotatable in said closing element, a clutch device arranged between the inner end of said shaft and said lock mechanism and adapted to lock the shaft to the casing so as to be 70 rotatable therewith or permit the casing to rotate on the shaft.

4. In combination, a cup-shaped casing, 75 lock mechanism arranged in the closed end of the casing, said casing having a key opening in the vicinity of said mechanism, a closing element detachably secured in the open end of said casing, a shaft extending through and rotatable in said closing element, said shaft having an annular enlargement 80 thereon on the inner side of said closing element, an antifriction thrust bearing between said enlargement and the inner face of said closing element, and means within the casing and controlled by said lock 85 mechanism for either clutching the casing to the shaft so as to be rotatable therewith or leave the casing free to rotate on the shaft.

5. In combination, a cup-shaped casing, 90 lock mechanism arranged in the closed end of the casing, said casing having a key opening in the vicinity of said mechanism, a closing element detachably secured in the open end of said casing, a shaft extending 95 through and rotatable in said closing element, a spacing sleeve substantially filling the casing and abutting at its ends respectively against said closing element and a part rigid with the casing, and means located within the sleeve and controlled by said lock mechanism for alternately clutching the casing to the shaft so as to prevent relative rotation between the same and permitting the casing to rotate freely on the 100 shaft.

6. In combination, a casing, a shaft extending into said casing, a lock mechanism within the casing having a rotatable device aligned with said shaft, a thrust bearing 110 between said device and the inner end of said shaft, and clutch mechanism arranged within the casing and controlled by said device in order alternately to lock said casing to the shaft for rotation therewith and leave the casing free to rotate on the shaft.

115 7. In combination, a cup-shaped casing, a lock adapter fixed within the closed end of the casing, a closing element detachably arranged within the open end of the casing and having an inwardly-directed hub, a shaft extending into the casing through the hub portion of said closing element, said shaft having an enlargement thereon beyond the inner end of said hub, a thrust bearing 120 between said enlargement and said hub, guides projecting toward the open end of said casing from said lock adapter, a sleeve-like member mounted in said guides and of such a length that it may move a limited 125

distance along said guides, said sleeve-like part extending at one end over and around said hub; a lock mounted in said adapter, means controlled by said lock for moving said sleeve-like part along said guides between a working position and an idle position, and, the inner end of said shaft and said sleeve-like part having cooperating

clutch elements attached to lock the casing to the shaft for rotation therewith in said working position and leave the casing free to rotate on the shaft in said idle position.

In testimony whereof, I sign this specification.

ADAM GABRIEL.
